UNITED STATES PATENT OFFICE

ALFRED H. HUMPHREY, OF NEW YORK, N. Y.

GAS-BURNER.

1,396,210.

Specification of Letters Patent.

Patented Nov. 8, 1921.

Application filed June 12, 1920. Serial No. 388,611.

To all whom it may concern:

Be it known that I, ALFRED H. HUMPHREY, a citizen of the United States, residing at New York, county of New York, State of New York, have invented certain new and useful Improvements in Gas-Burners, of which the following is a specification.

This invention relates to improvements in gas burners.

10 My improved gas burner is especially designed by me for embodiment in gas stoves of the type shown in my Letters Patent No. 1,280,740, issued October 8, 1918, although adaptable for use in other relations.

15 The main objects of this invention are:

First, to provide an improved burner having a very efficient combustion of gas both when burning with a full supply of gas and when turned down or burning with a limited supply of gas, and throughout the intermediate variations.

Second, to provide an improved gas burner which provides an efficient combustible mixture of air and gas throughout a wide range 25 of gas pressure or supply.

Further objects, and objects relating to structural details, will definitely appear from the detailed description to follow.

I accomplish the objects of my invention by the devices and means described in the following specification. The invention is clearly defined and pointed out in the claims.

A structure which is a preferred embodiment of my invention is clearly illustrated 35 in the accompanying drawing forming a part of this specification, in which:

Figure I is a front elevation of a gas burner embodying the features of my invention.

40 Fig. II is a detail vertical section through one of the burner tubes and nozzles.

Fig. III is an enlarged top view of one of the burner nozzles.

45 Fig. IV is a vertical central section of one of the nozzles on a line corresponding to line 4—4 of Fig. III.

Fig. V is a detail side elevation of one of the nozzles illustrating a jet of gas as issuing therefrom.

50 Fig. VI is a cross section on a line corresponding to line 6—6 of Fig. V, illustrating the shape of the jet of gas.

In the drawing, similar reference characters refer to similar parts throughout the 55 several views, and the sectional views are

taken looking in the direction of the little arrows at the ends of the section lines.

Referring to the drawing, my improved gas burner as illustrated comprises a plurality of burner tubes 1 formed as an integral casting, the tubes being connected by the vertical web 2. The burner tips 3 are provided with bars 4 disposed in a uniformly spaced relation as shown in my Patent No. 1,245,346, dated November 6, 1917.

The burner body is supported with the ends of the burner tubes in a spaced relation above the manifold 5. The manifold is provided with a plurality of tips 6 having oblong slot-like delivery orifices 7. The nozzles 6 are disposed centrally below the burner tubes so as to deliver into their lower open ends as shown in Fig. II. The space between the manifold and the lower ends of the tubes is unobstructed to permit a free circulation of air around the nozzles and into the lower ends of the burner tubes.

The jet orifice 7 is of such shape that a flat upwardly flaring forked jet 8 as illustrated in Fig. V is delivered therefrom.

The lower portion of the burner tube is of substantially uniform diameter and expands into the tip portion 3 which is also of substantially uniform diameter although considerably larger than the lower portion.

By thus forming and arranging the parts, I provide a burner which is efficient when the burner is using a full supply of gas or when the supply is reduced to a minimum, an effective combustible mixture being provided throughout the variations of gas supply.

I have illustrated my improvements as I have adapted them commercially in multiple burners for gas stoves of the type shown in my said patent. I have not attempted to illustrate or describe other adaptations or embodiments as I believe the disclosure made will enable those skilled in the art to which my invention relates to embody or adapt the same as may be desired.

Having thus described my invention, what I claim as new and desire to secure by Letters Patent is:

1. In a gas burner, the combination of a burner body comprising a plurality of burner tubes open at their lower ends and having burner tips provided with bars disposed in a uniformly spaced relation, said tubes being unobstructed from end to end, a gas delivery manifold, a valve for said

- manifold, and gas delivery nozzles therefor having oblong slot-like delivery orifices delivering forked streams of gas into the open ends of said burner tubes when the valve is adjusted to restrict the flow of gas through the nozzles, the space between the manifold and the burner tubes being unobstructed to permit a free circulation of air.
2. In a gas burner, the combination of a burner body comprising a plurality of burner tubes unobstructed from end to end, a gas delivery manifold, a valve for said manifold, and gas delivery nozzles therefor having oblong slot-like delivery orifices delivering forked streams of gas into said burner tubes when the valve is adjusted to restrict the flow of gas through the nozzles, the space between the manifold and the burner tubes being unobstructed to permit a free circulation of air.
3. In a gas burner, the combination of a burner tube open at its lower end and having a burner tip provided with bars disposed in a uniformly spaced relation, said tube being unobstructed from end to end, a burner valve, and a gas delivery nozzle having an oblong slot-like delivery orifice delivering a flat forked flaring stream of gas into the open end of said burner tube when the valve is adjusted to restrict the flow of gas through the nozzles.
4. In a gas burner, the combination of a burner tube unobstructed from end to end, a burner valve and a gas delivery nozzle having an oblong slot-like delivery orifice delivering a flat forked flaring stream of gas to said burner tube when the valve is adjusted to restrict the flow of gas through the nozzles.
5. In a gas burner, the combination of a burner tube having a lower portion of substantially uniform diameter expanding into a larger top portion of substantially uniform diameter, a burner valve and a gas delivery nozzle having an oblong slot-like delivery orifice delivering a forked flaring stream of gas to the bottom of said tube when the valve is adjusted to restrict the flow of gas through the nozzles.
6. In a gas burner, the combination of a burner tube having a lower portion of substantially uniform diameter expanding into a larger top portion of substantially uniform diameter, a burner valve and a gas delivery nozzle having an oblong slot-like delivery orifice delivering a forked flaring stream of gas to said tube when the valve is adjusted to restrict the flow of gas through the nozzles.
7. In a gas burner, the combination of a burner tube a burner valve and a gas delivery nozzle having an oblong slot-like delivery orifice delivering a forked flaring stream of gas to said tube when the valve is adjusted to restrict the flow of gas through the nozzles.

In witness whereof, I have hereunto set my hand and seal in the presence of two witnesses.

ALFRED H. HUMPHREY. [L.S.]
